DRAFT RIGGING

Donald S. Barrows, Rochester, N. Y., assignor to
The Symington Company, New York, N. Y., a
corporation of Maryland

Application September 10, 1928, Serial No. 305,075

8 Claims. (Cl. 213—69)

This invention relates to railway draft rigging and more particularly to a swivel butt coupler so formed that vertical angling between the parts is permitted to a slight degree as well as horizontal 5 angling.

The principal object of my invention, generally considered, is to provide a swivel butt coupler or one adapted to angle horizontally, so modified that it is also adapted to angle vertically to a 10 slight extent, novel means being also provided for holding the pivot pin connecting the parts of the coupler stem.

Another object of my invention is to provide a swivel butt coupler so modified that a small 15 amount of vertical angling is permitted due to tapering intercalated flanges on the coupler stem, associated swivel block, or both.

A further object of my invention is to provide a swivel butt coupler stem with a pivotally connected swivel block, some of the holes receiving the pivot means between said coupler stem and block being broached oval and clearance between the intercalated flanges on the connected parts being provided for permitting a slight amount of 25 vertical angling therebetween.

A still further object of my invention is to provide a coupler stem and pivotally connected swivel block, the pivot means between said parts being adapted to take the form of simple cylindrical 30 pins which extend to but do not intersect a slot for receiving a horizontal draft key for connecting said swivel butt coupler with an associated yoke, said swivel block being provided with bosses or lugs partly closing the inner ends of the pivot 35 means receiving apertures for supporting the adjacent ends of said pivot means, the outer ends of said pivot means being held in position by suitable retaining means on said swivel block.

Other objects and advantages of the invention 40 relating to the particular arrangement and construction of the various parts will become apparent as the description proceeds.

Referring to the drawings illustrating my invention, the scope whereof is defined by the ap- 45 pended claims:

Figure 1 is a plan of one embodiment of my swivel butt coupler, the associated horizontal yoke and connecting draft key being illustrated by dot and dash lines.

Figure 2 is a side elevational view, shown partly 50 in section on line 2—2 of Figure 1, the associated yoke being omitted.

Figure 3 is a horizontal sectional view on the line 3—3 of Figure 2, showing the swivel block 55 detached from the coupler stem.

Figure 4 is a plan of the coupler shank with the associated swivel block detached therefrom.

Figure 5 is a view corresponding to Figure 2 but showing a modification of my invention.

Figure 6 is a view corresponding to Figure 2 but 60 showing another modification of my invention.

Figure 7 is a plan, partly in central horizontal section, of another embodiment of my invention.

Figure 8 is a side elevational view, shown partly 65 in central vertical section, of the embodiment of my invention illustrated in Figure 7.

Referring to the drawings in detail, like parts being designated by like reference characters, and first considering the embodiment of my invention illustrated in Figures 1-4, inclusive, a 70 coupler 1 is shown with rearwardly extending flanges 2 and 3 on the stem or shank 4 thereof. Associated with said coupler shank is a swivel block or butt member 5, formed with intercalated flanges or webs 6, 7 and 8, which are so spaced 75 that they receive therebetween the flanges 2 and 3 on the coupler shank, registering apertures 9 and 10 being provided in the intercalated flanges on the coupler and swivel block, respectively, and extending through said apertures for pivotally 80 connecting said coupler and swivel block is pivot means 12.

In the present embodiment the pivot means 12 takes the form of a pair of simple cylindrical pins, the outer ends of which are held in place 85 by means of retainers 13 passing through spaced lugs 14 on the corresponding outer faces of the flanges 6 and 8 of the swivel block. In order to connect said coupler with the associated yoke 15 a slot 16 is provided for receiving the horizontal connecting draft key 17, said slot in the present embodiment being formed partly in the coupler shank 4 and partly in the intermediate flange 7 of the swivel block and extending be- 90 tween the pivot pins 12. In order to prevent interference between said pins and the draft key 17, lugs 18 are provided which partially close the apertures 10 in the bifurcated flange 7 between the inner ends of said pins 12, so that said pins are properly spaced, as indicated particularly in 100 Figure 2.

The extreme edges of the flanges 2 and 3 on the coupler shank are curved approximately coaxially with respect to the pin-receiving apertures 9 therein and the inner wall of the swivel block between the flanges 6 and 7 and 7 and 8 is formed on a corresponding curvature whereby 105 horizontal pivotal motion or angling between the parts, when assembled, is permitted. The ex- 110 treme edges of the flanges 6, 7 and 8 of the swivel

block are similarly formed coaxial with the pivot pin receiving apertures therethrough and the adjacent walls of the coupler butt are similarly curved for permitting the desired horizontal angling between the parts.

In order to permit a slight amount of vertical angling or pivotal motion about an axis angularly disposed with respect to the axis of the pivot pins 12 or pivot pin receiving apertures, the holes 9 through the flanges 2 and 3 for receiving said pins are preferably broached oval longitudinally of the coupler shank so that a slight amount of vertical angling between said pin and flanges is permitted. Such oval broaching is illustrated particularly in Figure 4. In order not to interfere with said vertical angling, clearance is necessarily provided between the intercalated flanges 2 and 3 on the coupler shank and 6, 7 and 8 on the swivel block. Such clearance in the present embodiment is provided by tapering the flanges 2 and 3 or decreasing them in thickness both ways from the pivot pin receiving apertures 9 therethrough, as illustrated most clearly in Figure 2. The clearance thus provided permits the desired amount of vertical angling therebetween without materially impairing the bearing areas between the parts for the transmission of draft or buffing forces.

Referring now to the embodiment of my invention illustrated in Figure 5, a form is there disclosed similar to that of the first embodiment, except that a full length or one-piece pin 12^a is provided for connecting the shank 4^a of the coupler 1^a to the swivel block 5^a by extending through apertures 9^a in the flanges 2^a and 3^a on the shank and apertures 10^a in the flanges 6^a, 7^a and 8^a on the swivel block. In order to permit the use of a single full length pin 12^a, the lugs previously referred to and designated as 18 are eliminated, preferably by drilling out, so that they do not interfere with the pin 12^a. In the present embodiment the pin is formed with a notch 19 for receiving the rear edge of the associated draft key 17^a. Said draft key will, of course, tend to maintain the pin 12^a in position but in order to properly retain the pin without relying on the draft key, which is only in place after assembly with the associated yoke, pin retainers 13^a are provided above and below the pin 12^a extending through lugs 14^a on the upper and lower faces of the swivel block on either side of said pin. In the present embodiment the ends of the pin are notched, as indicated at 20, receiving the retainers 13^a therein, so that the turning of said pin is prevented.

In addition to the use of the full length pin in the present embodiment, the clearances 15^a between the flanges 2^a and 3^a on the coupler shank and 6^a, 7^a and 8^a on the swivel block are provided by tapering the swivel block flanges away from the coupler shank flanges on both sides of the pin 12^a rather than by tapering the flanges on the coupler shank as in the previous embodiment.

Said coupler shank flanges may be maintained with parallel faces, as in Figure 5, or they may be tapered in the same manner as the flanges 2 and 3 are formed in the first embodiment. This further modification is illustrated in Figure 6 in which the flanges 6^b, 7^b and 8^b on the swivel block 5^b are tapered, as in Figure 5, while the flanges 2^b and 3^b on the coupler shank 4^b are tapered, as in Figures 1 and 2, whereby a greater amount of clearance may be conveniently provided for permitting vertical as well as horizontal angling between said coupler and swivel block.

It will be understood that the embodiments illustrated in Figures 5 and 6 are identical, except that a coupler shank with tapered flanges is used in the construction illustrated in Figure 6, instead of a shank with plain flanges or flanges with parallel faces.

Referring now to the embodiment of my invention illustrated in Figures 7 and 8, a form is there disclosed in which a coupler 1^c is formed as before with rearwardly extending flanges 2^c and 3^c on the stem or shank 4^c thereof. These flanges are intercalated with and embraced by corresponding flanges 6^c, 7^c and 8^c on the swivel block 5^c.

The flanges 2^c and 3^c on the coupler stem and 6^c, 7^c and 8^c on the swivel block are provided with registering apertures 9^c and 10^c, respectively, for receiving pivot means 12^c. The pivot means in the present embodiment is shown as a full length pin supported at its lower end on an integral shelf 21 and held against undesired upward movement by means of a cotter 22 extending through lugs 23 on opposite sides of the pin-receiving apertures 10^c. As in the previous embodiments, the pin 12^c is provided with a notch 19^c for receiving the rear edge of the associated key 17^c for connecting the coupler with the associated yoke 15^c, said key for that purpose passing through the slot 16^c in the coupler shank 4^c and corresponding slots in the arms of the yoke 15^c.

In the present embodiment instead of forming the extreme edges of the flanges 2^c and 3^c on the coupler shank as cylindrical surfaces about the axis of the pin-receiving apertures 9^c, said edges are preferably formed as zones of a sphere, the center of said sphere preferably lying at the intersection of the longitudinal center line of the coupler shank with the forward edges of the apertures 9^c through the flanges 2^c and 3^c. The engaging surfaces on the swivel block 5^c are, of course, correspondingly curved so that full bearing areas for the transmission of buffing forces are provided between the edges of the rear surfaces of the flanges 2^c and 3^c and the corresponding surfaces of pocket portions of the associated swivel block 5^c. The purpose of so curving these engaged surfaces on the connected parts is to permit not only the usual horizontal angling therebetween but also a slight amount of vertical angling, thereby providing for a limited amount of universal angling between the coupler stem and swivel block. The reason for positioning the center of the spherical surfaces as before specified is that this point is thought to be a convenient and logical location for the spherical bearing areas. The outer or forward surfaces on the flange 7^c which is bifurcated by the draft key receiving slot 16^c are also preferably formed as surfaces of a sphere concentric with the spherical surfaces on the flanges 2^c and 3^c and the engaging surfaces on the coupler stem are correspondingly curved, thereby augmenting the bearing area provided for the transmission of buffing forces from the coupler stem to the swivel block and onto the associated cushioning mechanism (not shown).

In order to permit the vertical angling provided for by the spherical curving of the flanges 2^c, 3^c and 7^c, the holes or pivot pin receiving apertures 9^c through the flanges 2^c and 3^c are preferably broached oval longitudinally of the coupler shank, as in the previous embodiments, so that a slight amount of vertical angling between the pin and flanges is permitted. In order not to interfere with such vertical angling clearance

was heretofore necessarily provided between the intercalated flanges on the coupler shank and the swivel block. Such clearance in the present embodiment is formed by tapering the flanges 2° and 3° or decreasing them in thickness both ways from the forward end or side of the pivot pin receiving apertures 9 therethrough, as illustrated most clearly in Figure 8. This location is chosen as it corresponds most closely with the center of the spherical surfaces on said flanges. If the center of the spherical portions is changed, a corresponding change would occur in the location from which the flanges are tapered. The clearance thus provided and designated by the reference character 15^d permits the desired amount of vertical angling between the parts, the bearing areas for the transmission of buffing forces being maintained on account of the spherical bearing surfaces. The extreme edges of the flanges 6^c and 8^c are shown as cylindrical rather than corresponding in curvature with the other flanges, sufficient clearance, however, being provided between the edges of said flanges and the corresponding surfaces on the coupler stem for permitting the desired angling between the parts.

If desired the vertical dimensions of the flanges 2° and 3° on the coupler shank and the corresponding overall vertical dimension of the swivel block may be increased to compensate for the tapering of the flanges 2° and 3° to thereby maintain the normal bearing area for the transmission of buffing forces.

From the foregoing it will be understood that I have devised a swivel butt coupler in which a small amount of vertical angling between the coupler shank and associated swivel block, in both directions from their normal relation, is permitted by tapering some or all of the intercalated flanges on said coupler shank and swivel block, whereby the necessary clearance for such vertical angling is provided. Clearance between the pin or pins connecting the coupler stem and swivel block is preferably provided by broaching the pin receiving apertures in the coupler stem oval in a longitudinal direction rather than by merely forming said holes larger than the pin or pins to the necessary extent.

Although I have shown preferred embodiments of my invention, it will be understood that I do not desire to be limited to the exact details of construction shown and described, because obvious modifications within the scope of the claims will occur to persons skilled in the art.

Having thus described my invention, I claim:

1. A coupler stem comprising a pair of members with horizontally disposed intercalated flanges, vertical pivot means extending through said flanges for connecting said members for horizontal angling and providing for the transmission of draft forces therebetween, some of said flanges having walls receding from the adjacent walls of the other member, and said pivot means being loosely received, to provide clearance for permitting both up and down pivotal motion between said members from normal relation.

2. A coupler stem comprising a plurality of members with intercalated flanges, a slot formed partly in each of said members and adapted to receive a horizontal draft key, said flanges being formed with registering apertures, pivot means extending through said apertures from below to but not intersecting the slot for said draft key, pivot means extending through said apertures

from above to but not intersecting the slot for said draft key, lugs disposed between said pivot means for preventing interference thereof with said draft slot, and means engaging the outer ends of said pivot means for holding them in place.

3. A coupler stem comprising a plurality of members with intercalated flanges, a slot formed in said stem and adapted to receive a horizontal draft key, said flanges being formed with registering apertures, pivot means extending through said apertures from below to but not intersecting the slot for said draft key, pivot means extending through said apertures from above to but not intersecting the slot for said draft key, said pivot means providing for the transmission of draft forces, means formed on one of said members, positioned beyond said slot and disposed between said pivot means for preventing interference thereof with said slot, and means engaging the outer ends of said pivot means for holding them in place, the outer edges of the flanges on one member engaging correspondingly pocketed portions of the other member.

4. In combination, a coupler stem, an associated member disposed rearwardly thereof, said coupler stem and member having intercalated flanges, said flanges having registering apertures, a slot adapted to receive a draft key and formed in said associated stem and member adjacent and intersecting the apertured portions, pivot means extending through said apertures, from below but not intersecting said slot and from above but not intersecting said slot, means formed on one of said pivotally connected members and disposed between said pivot means for spreading them a given distance to keep them out of said slot, and means limiting upward movement of the upper pivot means and downward movement of the lower pivot means.

5. In combination, a coupler stem, an associated member disposed rearwardly thereof, said coupler stem and member having generally parallel intercalated flanges, said flanges having registering apertures, some of said flanges being tapered to provide clearance permitting angling between said stem and member at right angles to the planes of said flanges, a slot adapted to receive a draft key and formed in said associated stem and member adjacent and intersecting the apertured portions, pivot means, providing for angling in a plane generally parallel to said flanges, extending loosely through said apertures, from below but not intersecting said slot and from above but not intersecting said slot, means formed on one of said pivotally connected members and disposed between said pivot means for spreading them a given distance to keep them out of said slot and from interfering with said angling, and means limiting upward movement of the upper pivot means and downward movement of the lower pivot means.

6. A coupler stem comprising a pair of members with intercalated flanges, pivot means extending through said flanges for connecting said members for relative angling and providing for the transmission of draft forces therebetween, some of said flanges having walls receding from the adjacent walls of the other member and said pivot means being loosely received to provide clearance for permitting pivotal motion at right angles to said first-mentioned angling movement.

7. A coupler stem comprising a pair of members with flanges normally disposed horizontally and intercalated with one another, pivot means

normally disposed vertically and extending through said flanges for connecting said members for angling with respect to one another and providing for the transmission of draft forces therebetween, the flanges of one of said members tapering in thickness forwardly and rearwardly from said pivot means, and said pivot means being loosely received for providing clearance to permit angling between said members at right angles to that provided for by said pivot means.

8. A coupler stem comprising a pair of members with flanges normally disposed horizontally and intercalated with one another, pivot means

normally disposed vertically and extending through said flanges for connecting said members for angling with respect to one another and providing for the transmission of draft forces therebetween, the flanges of both of said members tapering in thickness forwardly and rearwardly from said pivot means, and said pivot means being loosely received for providing clearance to permit angling between said members at right angles to that provided for by said pivot means.
